UNITED STATES PATENT OFFICE.

JOHN F. WOLVEN, OF ST. CLAIR, MICHIGAN.

STOVE.

SPECIFICATION forming part of Letters Patent No. 240,065, dated April 12, 1881.

Application filed January 31, 1881. (No model.)

To all whom it may concern:

Be it known that I, JOHN F. WOLVEN, of the city and county of St. Clair, and State of Michigan, have invented an Improvement in Heating-Stoves, of which the following is a specification.

The nature of this invention relates to useful improvements in that class of heating-stoves wherein the products of combustion are prevented from escaping until they have nearly or quite parted with their heat by radiation, heating currents of air, which, being in constant circulation, are drawn from the floor and carried upward through the stove, and are there discharged in a highly-heated condition.

The invention consists in the peculiar construction of the various parts, their various combinations, and their operation, as more fully hereinafter described.

Figure 1 is a vertical central section of my improved stove. Fig. 2 is a horizontal section on the line 2 in Fig. 1. Fig. 3 is a like view on the line 3 in Fig. 1. Fig. 4 is a plan view of the top. Fig. 5 is a plan of the bottom.

In the accompanying drawings, which form a part of this specification, A represents the shell of the stove, B the bottom plate, and C the top plate thereof. A series of tubes, D, pass through the top and bottom immediately outside of the shell and open to the air above and below the stove, said tubes being secured to said top and bottom plates in any convenient manner, and with tight joints.

E is the ash-pit, upon the top of which is supported the circular and flaring fire-pot F and the grate G. These members may be supported in any desired way.

H are a series of larger tubes enclosing the tubes D, opening at their lower ends into a chamber, I, (in which is suspended the magazine or feeder T,) and into the chamber J at their upper ends. This chamber is formed by the top plate, C, and the plate K and the circular wall L. The chamber I is formed by the shell A, the lower ring, M, base-plate B,

and flat ring N, which supports the lower ends of the tubes H and the shell A. The upper end, O, of the feeder flares to one side, as shown in Fig. 1, to receive fuel through the opening P in the plate K and the hole Q in the plate C, the latter hole being provided with a removable cover.

R is the exit through which the products of combustion pass to the chimney-flue, and S a sliding damper affording direct communication between chambers I and J when a direct draft is required. The open top of the magazine is provided with a damper or door. (Not shown in the drawings.)

In practice, after the fire is well started, the damper S should be closed, when the only avenue of escape for the products of combustion is afforded through the tubes or flues H to the chamber J, and thence out at the exit R. In this way the air in the tubes D becomes highly heated and escapes at their open tops, being replaced by the colder air drawn in from below. By this construction radiation is also obtained from the tubes, as well as from the wall of the stove which they surround.

What I claim as my invention is—

1. A heating-stove having the interior shell, A, forming the combustion-chamber, in combination with the exterior fire-tubes, H H, each fire-tube H surrounding an air-tube, D, which passes entirely through the stove, whereby direct radiation is obtained from the shell, from the fire-tubes, and from the air-tubes, substantially as described.

2. In a heating-stove, the combination of the shell A, bottom B, top C, chambers I J, grate G, ash-pit E, feeder T, and the air-pipes D D, each air-pipe passing entirely through a separate fire-tube H outside of the shell, substantially as described.

JOHN F. WOLVEN.
